UNITED STATES PATENT OFFICE.

ROY G. DONALDSON, OF CRESTLINE, OHIO.

GRATE.

1,324,803.

Specification of Letters Patent. Patented Dec. 16, 1919.

Application filed July 23, 1918. Serial No. 246,362.

To all whom it may concern:

Be it known that I, ROY G. DONALDSON, a citizen of the United States, residing at Crestline, in the county of Crawford and 5 State of Ohio, have invented certain new and useful Improvements in Grates, of which the following is a specification.

My invention relates to improvements in grates, adapted for use in connection with 10 railway locomotives, stationary boilers or the like.

An important object of the invention is to provide a grate of the above mentioned character, having means to properly shake 15 the coal, effectively slice or break up clinkers, and discharge the clinkers from the firebox.

Other objects and advantages of the invention will be apparent during the course of the following description.

20 In the accompanying drawings forming a part of this specification and in which like numerals are employed to designate like parts throughout the same,

Figure 1 is a plan view of apparatus embodying my invention,

Fig. 2 is a longitudinal sectional view taken on line 2—2 of Fig. 1,

Fig. 3 is a transverse sectional view taken on line 3—3 of Fig. 1,

30 Fig. 4 is a similar view taken on line 4—4 of Fig. 1,

Fig. 5 is a perspective view of one of the movable side grate members,

Fig. 6 is a similar view of the central 35 movable grate member,

Fig. 7 is a fragmentary perspective view of a stationary transverse grate member,

Fig. 8 is a similar view of a stationary longitudinal grate member, and,

40 Fig. 9 is a perspective view of a slicer blade.

In the drawings, wherein for the purpose of illustration is shown a preferred embodiment of my invention, the numeral

45 10 designates a horizontal preferably rectangular frame having a pair of longitudinal coal discharging hoppers 11 arranged

therein. These hoppers are stationary. Each hopper, as shown in Fig. 3, embodies

50 upwardly diverging discharge passages 12. The space between the upper ends of these

passages 12 is covered by longitudinal horizontal grate sections 13. Arranged at

55 spaced intervals between the longitudinal grate sections 13 are transverse grate sec-

tions 14, shown more clearly in Figs. 1 and 4. Beneath the transverse grate sections 14, the hoppers 11 have their lower ends closed or covered by deflectors 15, having inclined upper faces 16. Openings 17 60 are formed in the opposite side walls of the diverging passages 12 and permit of the ashes or the like passing therethrough into the ash-pit.

Traveling longitudinally of and beneath 65 each discharging hopper 11 is an endless coal or fuel conveyer 18, having feeding elements or drags 19, to feed the fuel forwardly. The fuel is delivered into a hopper 20, and carried by the conveyer into the 70 passages 12 and is forced upwardly through the same, to be fed upon the grate members. As no claim is made to the feeding mechanism *per se* in this application, no detailed description of the same is given, such feeding mechanism being shown and described 75 in my copending application for underfeed stoker, filed July 23, 1918, Serial No. 246,363.

Extending longitudinally and centrally 80 of the frame 10 is a central cleansing and agitating apparatus embodying a longitudinal shaft 21, suitably secured to the ends of the frame 10. Mounted to turn upon this shaft are cleaning elements 22, arranged 85 in end to end relation. Each cleaning element, as more clearly shown in Fig. 6, embodies a sleeve 23, pivotally receiving the shaft 21. This sleeve extends upwardly in the form of a tapered blade 24. Extending 90 laterally upon opposite sides of the blade 24 are spaced fingers or bars 25 and 26, the flanges 26 having upwardly extending angular projections 27, formed thereon. Each finger 26 is further provided with a 95 depending fire retaining or supporting element 28, preferably tapered, as shown.

Arranged near and upon opposite sides of the central cleaning apparatus are stationary grate sections 29. As clearly shown 100 in Fig. 1, each grate section 29 embodies sets of inwardly projecting bars or fingers 30, the inner ends of the bars in the two sets being spaced for providing a longitudinal opening 31. This longitudinal opening 105 is adapted for the reception of swinging slicer blades 32, which is curved in transverse section, as shown. The slicer blades 32 are provided at their ends with cranks 33, pivoted to the grate sections 30, 110

as shown at 34. In operation, the slicer blades 32 are simultaneously swung inwardly, thereby cutting into the clinkers which may have formed, while the cleaning element 22 is swung upon its pivot, serving to coat with the slicer blades to break up the clinkers. The fire retaining elements 28 are swung upwardly simultaneously with the movement of the slicer blades, to prevent the coal and clinkers from improperly falling from the grate. These fire retaining elements in their elevated positions form ash and clinker receiving pockets which, upon the movement of these elements to their lower positions, discharge the ash and clinker contained in such pockets. As is clearly shown, the grate sections 29 are transversely inclined and extend downwardly from the hopper 11.

Arranged upon the outer sides of the troughs 12 are side cleaning apparatuses, each of which comprises inner stationary grate sections 35, embodying short and long transverse bars or fingers 36 and 37. The grate sections 35 may be attached to the hoppers 11. Arranged outwardly of and near the grate sections are coacting cleaning elements 38, three of which constitute a unit. Each cleaning element 38 embodies a sleeve 39, mounted to rotate upon a horizontal longitudinal shaft 40 suitably secured to the frame 10. Extending inwardly from the sleeve 39 are clinker bars 41, having lower faces 42, which are curved, as shown. The sleeve 39 carries outwardly extending bars or fingers 43, which are angularly arranged, as shown.

Extending longitudinally of the frame 10 and upon one side thereof is a rock-shaft 44, turned by means of a gear 45, driven by any suitable means. Rigidly secured to the rock-shaft 44 and depending therefrom are cranks 46, three in number, corresponding to the different units of the apparatus. In connection with each unit there is a transverse reciprocating pitman 47, having pivotal connection with a link 48, pivoted to the lower end of the crank 46. At its center, the pitman 47 is provided with an upwardly extending projection 49, carrying a pin or bolt 50 operating in a slot 51, formed in a crank 52 rigidly secured to the sleeve 23 of the central cleaning element.

This central cleaning element also serves to operate the corresponding pair of slicer bars 32. Pivotedly connected with one end of each slicer bar is a link 52', as shown at 53. One link 52' is pivotally connected with a bell-crank lever 54, as shown at 55, while the other link 52' is pivoted to a bell-crank lever 56, as shown at 57. The bell-crank lever 54 is pivoted at 58 and the bell-crank lever 56 is pivoted at 59. A link 60 is pivoted to the bell-crank lever 56 and with the upstanding arm of the bell-crank lever 54,

as shown at 61. At its upper end the bell-crank lever 54 carries a laterally extending pin 62, arranged between lugs 63 and 64, formed upon the sleeve 23. It is thus apparent that when the sleeve is turned clockwise the lug 63 will contact with the pin 62 thereby swinging the bell-crank levers 54 and 56 upon their pivots and forcing the slicer blades 32 upwardly and inwardly. When the sleeve is turned in the opposite direction the lug 64 returns the slicer blades to the lowered position.

At its right end, the pitman 47 has pivotal connection with a link 65, pivoted to a depending crank 66, rigidly secured to the sleeve 39. At the left end, the pitman 47 has pivotal connection with a bell-crank lever 67, pivotally supported at 68. The bell-crank lever 67 has pivotal connection with the link 69, pivoted to a crank 70, rigidly secured to the sleeve 39 of the left side cleaning element. It is obvious that the side cleaning elements are swung simultaneously in opposite directions.

The operation of the apparatus is as follows:

The coal is fed into the hoppers 20, and is carried by the conveyers 18 into the passages 12 of the troughs and fed upwardly upon the grate members, where combustion takes place in the usual manner. When it is desired to shake the grate, the shaft 44 is rocked. This movement of the shaft causes the central and side cleaning apparatuses to operate. When the shaft is turned sufficiently in a clockwise direction, the slicer blades 32 are forced upwardly and inwardly, which tends to break up or slice clinkers accumulating in proximity thereto. With this movement of the slicer blades, the shaft 21 is turned and the projections or teeth 27 cut or break off the clinker, operating in conjunction with the slicer blades and discharge the same from the grate, through the opening occurring at the right, at the cleaning element, the retaining elements 28 being then elevated and serving to support the fire and prevent the coal from improperly falling from the grate.

Simultaneously with this movement of the slicer blades, the side cleaning apparatuses are operated. The members 41 are swung upwardly and outwardly and the straight edges thereof serve to cut or pinch off clinkers which may be formed in proximity thereto, discharging the same from the top of the grate, through the opening occurring at the outer sides thereof, the curved surface 42 of these elements serving to support the coal and prevent the discharge of the same.

It is to be understood that the form of my invention herewith shown and described is to be taken as a preferred example of the same, and that various changes in the shape, size, and arrangement of parts may be re-

sorted to without departing from the spirit of the invention or the scope of the subjoined claims.

Having thus described my invention, I

5 claim:

1. In a grate of the character described, the combination with a pair of relatively stationary grate sections which are transversely inclined with respect to the grate 10 and extend downwardly toward their inner edges and have longitudinal openings formed therethrough, of cleaning apparatus arranged between and near the inner lower edges of the inclined grate sections and provided with upwardly extending projections 15 which are disposed to coact with the inner lower edges of the grate sections for breaking up the clinker, means for turning the cleaning apparatus upon its longitudinal axis, transversely curved slicer-blades pivotally supported outwardly of and near the grate sections and arranged to move within the longitudinal openings of the same, said 20 slicer-blades being adapted to assume an upper position whereby they project above and across the inclined grate sections and are spaced from the cleaning apparatus, the inner edges of the slicer-blades being then spaced, and means to swing the slicer-blades 25 upon their pivots.
2. In a grate of the character described, the combination with a pair of relatively stationary grate sections which are spaced and transversely incline with respect to the grate 30 and extend downwardly toward their inner edges and have longitudinal openings formed therethrough, of cleaning apparatus arranged between and near the inner lower edges of the inclined grate sections and including upwardly projecting members for coaction with the lower edges of the in- 35 clined grate sections for breaking up the clinker, supporting elements arranged at an angle to the teeth and adapted to assume a position between the inclined grate sections 40 to prevent the improper discharge of the fuel, means to turn the cleaning apparatus upon its longitudinal axis, transversely curved slicer-blades pivotally supported outwardly of and near the inclined grate sections and arranged to move within the longitudinal openings of the same, said slicer-blades being adapted to assume an upper position whereby they project above and across portions of the inclined grate 45 sections and are spaced from the cleaning apparatus, the inner edges of the slicer-blades being then spaced, means to swing the slicer-blades upon their pivots.
3. In a grate of the character described, the combination with a pair of spaced relatively stationary grate sections which are transversely inclined with respect to the grate and extend downwardly toward their inner edges and have longitudinal openings 50 formed therethrough, of cleaning apparatus arranged between and near the inner lower edges of the inclined grate sections and adapted to coact with such inner lower edges in breaking up the clinker, means for turning the cleaning apparatus upon its longitudinal axis, slicer-blades adapted for movement within the longitudinal openings of the inclined grate sections and adapted when shifted to the upper position to be disposed 55 above and spaced from the cleaning apparatus and serving to cut off the clinker and prevent its upward movement by the turning of the cleaning apparatus, and means to move the slicer-blades.

In testimony whereof I affix my signature.

ROY G. DONALDSON.
